UNITED STATES PATENT OFFICE.

WALTER C. McLAREN, OF OAKLAND, CALIFORNIA.

TRUNDLE TOY.

Application filed August 29, 1925. Serial No. 53,298.

The present invention relates to improvements in toy vehicles and its principal object is to provide a vehicle extremely simple of construction that effectively simulates in 5 appearance a locomotive and in which by a simple mechanism the motion of the draw bars and the connecting rod characteristic of the locomotive is reproduced. In this connection it is proposed to shape and print 10 a simple board, standing on edge, to simulate a locomotive in side elevation, to support the front end of the board on a wheel, to provide a sliding bar along the side of the board and to cause the wheel to recipro- 15 cate the sliding bar when the whole device is advanced by means of a handle disposed at the rear end of the board.

Further objects and advantages of my invention will appear as the specification pro- 20 ceeds.

The preferred form of my invention is illustrated in the accompanying drawing, in which:—

Figure 1 shows a side elevation of my de- 25 vice.

Figure 2 is a vertical section taken along line 2—2 of Figure 1.

Figure 3 is a vertical section taken along line 3—3 of Figure 1.

Figure 4 is an enlarged fragmentary de- 30 tail view in side elevation of the device as viewed from point 4 in Fig. 3.

While I have shown only the preferred form of the invention, I wish to have it 35 understood that various changes or modifications may be made within the scope of the claims hereto attached without departing from the spirit of the invention.

Referring to the drawing in detail:

A plate or board 1, is shaped and prefer- 40 ably painted to simulate in side elevation a locomotive, presenting the characteristic features of the same, such as the boiler barrel 2, the engineer's room 4, the smoke box 6, the smoke stack 7, the bell 8, the dome 9, the headlight 11, the pilot or cow-catcher 12, the engine 13, and the wheels 14. The front end of the board is preferably recessed as shown at 16 so as to allow the board to straddle a wheel 17 on the axle 18 of which the front end of the board is supported. From the rear end of the board extends a handle 19, and the board, wheel and handle are

dimensioned to allow a boy of appropriate age to push the toy ahead of him by operating the handle while the wheel engages with the surface of the pavement.

Alongside of the board, preferably on each side thereof, is supported a sliding bar 21, the two bars resting on pins 22, riding in a horizontal slot 23 in the board. These bars are arranged relative to the inactive wheels 14 shaped or painted on the board to simulate the drawbars of the locomotive, that is, comparatively near the hubs or axles 65 of the said wheels. The axle 18 of the active front wheel 17 has a crank 24 at each end and the ends of these cranks are connected to the front end of the sliding bars 21 by means of connecting rods 26 whereby 70 reciprocating motion is imparted to the slide bars 21 when the wheel 17 revolves. The top faces of the slide bars 21 may be made corrugated as shown at 27 and a spring 28 be arranged to cause its free end to ride 75 on the slide bars to produce a rattling sound while the said bars reciprocate.

It will be seen that in this manner a realistic reproduction of a locomotive is obtained by a very simple mechanical contrivance and 80 at the same time a toy produced that gives ample opportunity for healthy exercise and for development of skill.

Having described my invention, what I claim is:—

1. A toy comprising a vertical plate made to simulate in side elevation a locomotive and presenting inactive wheels on the sides thereof in simulation of locomotive wheels, a horizontal bar slidable along said plate 90 in the vicinity of the wheel hubs, an active wheel supporting the front end of the plate, an operating handle extending from the rear end of the plate allowing a child to advance the wheel on the road by pushing on 95 the handle and an operative connection between the wheel and the bar causing the latter to be reciprocated in simulation of the reciprocating motion of the draw bar of a locomotive when the wheel revolves.

2. A toy comprising a vertical plate made to simulate in side elevation a locomotive and presenting inactive wheels on the sides thereof in simulation of locomotive wheels, a horizontal bar slidable along said plate 100 in the vicinity of the wheel hubs, an active

wheel supporting the front end of the plate, an operating handle extending from the rear end of the plate allowing a child to advance the wheel on the road by pushing on the handle and a connecting rod having one end pivoted relative to the wheel at a distance from the center thereof and having its

other end pivoted to the bar for reciprocating the latter in simulation of the draw bar of a locomotive when the wheel revolves. 10

In testimony whereof I affix my signature.

WALTER C. McLAREN.
